INTERNAL COMBUSTION ENGINE COMPRESSION CONTROL

George Franklin Rightmyer, Gouglersville, Pa.

Application August 25, 1937, Serial No. 160,903

4 Claims. (Cl. 192—01)

This invention appertains to new and useful improvements in internal combustion engine controls and more particularly to a control for the compression of the cylinders, whereby when desired, the compression can be released to permit coasting of the companion vehicle while the transmission is in driving gear.

An important object of the invention is to provide a compression release of the character stated wherein various controls of the vehicle must be in a definite position before the release can be accomplished.

Another important object of the invention is to provide a control of the character stated which will be positive acting and not susceptible to the ready development of defects.

In the drawings:

Figure 1 represents a side elevational view of an internal combustion engine and drive thereon from showing the invention installed thereon.

Figure 2 is a perspective view of an internal combustion engine with the valves cover removed showing the spring lifting means.

Figure 3 is a fragmentary sectional view 25 through the structure shown in Figure 2.

Figure 4 is an edge elevational view of the detent shown in Figure 1.

Figure 5 is a side elevational view of the tensioning means shown in Figure 1.

Figure 6 is an edge elevational view of the tensioning means.

Figure 7 is a perspective view of the inside disk of the tensioning unit.

Figures 8 and 9 represent the intermediate and 35 outer disks of the unit shown in Figure 6.

Figure 10 represents exploded perspective view of the parts of the detent.

Referring to the drawings wherein like numerals designate like parts, it can be seen in Figure 2 40 that numeral 5 generally refers to a conventional internal combustion engine in which are located the valve springs 6. The motor illustrated has a side cover permitting access to the springs 6 and in carrying out the present invention, a guide 45 bar 7 is mounted horizontally in the springs compartment and has a plurality of blocks 8 slidably mounted thereon, the bar 7 being polygonal in cross section so that the blocks 8 cannot rotate thereon.

50 The blocks are provided with round openings through which the rod 9 extends, the rod 9 being provided with a plurality of springs 10 each connected at one end to the bar and having its opposite end bearing against one side of a complementary block 8. The bottom of the springs

compartment has a slot 10a therein downwardly through which depends the arm 11 from the rod 9.

Obviously when the blocks 8 are moved to position under the spring cups 12, the valves 13 will be retained in elevated position so that compression in the cylinders cannot take place.

Numerical 14 generally refers to the detent which consists of a bracket arm 15 suitably secured to the engine structure. This arm 15 has the shaft 10 or pin 16 extending through its upper portion for supporting the sectors 17, 18, 19 and 20 each having an opening at its upper end for receiving the shaft 16. The lower and wider portions of the sectors are provided with the slots 21 which are 15 capable of registry to their fullest extent to allow movement therein of the loop 22, which loop is on the upper end of the rocker arm 23 fulcrumed as at 24. A tension spring 25 is interposed between the lower portion of this rocker arm 23 and 20 the motor proper.

Each of the sectors 17 to 20, inclusive, is provided with an ear 26. The ear 26 of the sector 20 is connected by the rod 27 to the joint 28 between the accelerator pedal 29 and the accelerator control rod 30. From the ear of the sector 19 extends the line 31 through the conduit 32 to the bell crank 33 which is controlled by the governor 34 located on the countershaft 35 and geared as at 36 with the driven shaft 37. 30

The sector 18 is provided with the line extension 38 which extends through the conduit 39 to the knob 40 projecting rearwardly of the instrument board 41.

The last sector 17 has its ear connected by 35 the rod 42 to the clutch pedal 43.

It can now be seen, that when the governor controlled line 31 is in proper position at a definite speed of the driven shaft, the accelerator control 30 not in operation, and the clutch pedal 40 43 in clutch-engaged position, operation of the knob 40 for swinging the sector 17 will bring all of the slots 21 into full registry so that the spring 25 can pull the rocker 23 which with the help of the tensioning unit 44 will shift the blocks 45 8 on the bar 7 for positioning the same under the springs 6 to prevent closing thereof.

The tensioning unit 44 consists of the disks 45, 46 and 47. The disk 46 is stationary and is secured by its extension 48 to the engine block. 50

Pintles 49-50 extend beyond opposite sides of the disk 46 and upon these pins the disks 47-45, respectively, are mounted for rotation.

The disk 46 has the concentric slot 51 therein registerable with the slot 52 in the disk 47, while 55

the disk 45 has the laterally extending pin 53 projecting through both of the slots. A spring 54 extends from the pin 53 to the lug 55 on the outside of the disk 47.

- 5 The disk 45 is provided with the ear 58 connected by the link 57 to the arm 11 of the block shifting structure shown in Figure 2. The disk 47 is provided with the ear 56 which is connected by the link 59 to the lower end of the rocker 23.
- 10 (See Figure 1.)

Obviously, as a result of the above operations, the rod 8 (see Figure 2) will be shifted, tensioning the springs 10 associated with those blocks 8 which will not pass under corresponding valve 15 spring cups 12 until the corresponding valve springs have become untensioned, whereupon the blocks 8 will be urged by those springs 10 under tension to move under the spring cups remaining unsupported by blocks 8, so that all of the 20 valves will be supported in open position. Thus no compression can take place, eliminating any resistive force to the free running of the vehicle, while the transmission is actually in gear.

- 25 While the foregoing specification sets forth the invention in specific terms, it is to be understood that numerous changes in the shape, size and materials may be resorted to without departing from the spirit and scope of the invention as 30 claimed hereinafter.

Having described the invention what is claimed as new is:—

1. In combination an internal combustion engine, valves for the said engine, holding means 25 for the valves to hold the same open to prevent compression and control means for the said holding means, said control means including a detent made up of a plurality of swingable sections having slots therein, said sections provided

with accelerator, driven shaft and clutch connections.

2. In combination an internal combustion engine, valves for said engine, holding means for the valves to hold the same open to prevent compression and control means for the said holding means, said control means including a detent made up of a plurality of swingable sections having slots therein, said sections provided with accelerator, driven shaft and clutch connections, 5 a connection between the said detent and the holding means.

3. In combination an internal combustion engine, valves for said engine, holding means for the valves to hold the same open to prevent compression and control means for the said holding means, said control means including a detent made up of a plurality of swingable sections having slots therein, said sections provided with accelerator, driven shaft and clutch connections, 15 a connection between the said detent and the holding means, said connection consisting of a loop disposed through the said slots and tensioning means for the said loop.

4. In combination an internal combustion engine, valves for said engine, holding means for the valves to hold the same open to prevent compression and control means for the said holding means, said control means including a detent made up of a plurality of swingable sections 20 having slots therein, said sections provided with accelerator, driven shaft and clutch connections, a connection between the said detent and the holding means, said last mentioned connection consisting of a rocker having a member disposed 35 through the said slot and tensioning means between the said rocker and the said holding means.

GEORGE FRANKLIN RIGHTMYER.
